CLAIM

The ornamental design for a brake controller, as shown and described.

DESCRIPTION

This application is related to U.S. patent application Ser. No. 14/248,078 (filed Apr. 8, 2014; now U.S. Pat. No. 9,346,439); and to U.S. Design patent application Ser. No. 29/487,425 (filed Apr. 8, 2014; now U.S. Pat. No. D787,391), the entire contents of each of which are incorporated by reference herein.

FIG. 1 is a perspective view of a second embodiment of a brake controller of our new design.

FIG. 2 is a front view of the brake controller of FIG. 1.

FIG. 3 is a back view of the brake controller of FIG. 1.

FIG. 4 is a right side view of the brake controller of FIG. 1.

FIG. 5 is a left side view of the brake controller of FIG. 1.

FIG. 6 is a top view of the brake controller of FIG. 1; and,

FIG. 7 is a bottom view of the brake controller of FIG. 1.

The portions of the figures depicted in broken lines are not part of the claimed design.
